UNITED STATES PATENT OFFICE.

PAUL F. BOEYE, OF ST. PAUL, MINNESOTA, ASSIGNOR TO WALDORF PAPER PRODUCTS COMPANY, A CORPORATION OF MINNESOTA.

METHOD OF CONSTRUCTING SHIPPING CASES.

Application filed November 8, 1926. Serial No. 146,872.

This invention relates to a method of folding flat blanks to form shipping cases of the type having a plurality of sides, adapted to be secured together at certain of the corners 5 by overlapping flaps.

Such shipping cases are constructed from sheets of heavy fibre board or corrugated board which are creased to facilitate folding to box shape. It has been found that the 10 cases can be constructed most economically by incorporating a plurality of separately cut blanks in each, but it will be evident that the folding of the several sides and holding them in box shape until secured together is 15 naturally a difficult, awkward operation, when attempted by a single operator. Thus, by the methods heretofore employed, the expense of assembling the blanks has been excessive. The method of the present invention 20 has proven particularly valuable when applied to cases of the type described and claimed in my Patent No. 1,607,050, dated November 16, 1926. In such cases, a main blank is provided, which forms the bottom, 25 and at least two sides of the case and also flanges for securing the ends of these sides to the other blanks or sides of the box. These flanges, which are located at the ends 30 of the case, must be folded so as to overlie the exterior surface of both ends of the case.

It is my object to provide a method of folding and retaining the several sides and flanges in proper relation until they can be 35 permanently secured together. Other objects will appear and be more fully pointed out in the following specification and claims.

Referring to the drawings, Figure 1 is a side elevation of a stack of blanks, supported upon a table suitable for carrying out 40 my invention, the table being shown in central, vertical section; Fig. 2 is a perspective view of one of the shipping cases in finished form; Fig. 3 is a plan view of the flat blanks forming a case, secured together, 45 and ready for folding; Fig. 4 is a plan view of the table with a stack of blanks in place and showing one of the blanks partially folded; Fig. 5 is a longitudinal section through one of the boxes with the cover flaps 50 partially open and Fig. 6 is a vertical section through a portion of the table and showing a blank after the second folding operation.

As best shown in Fig. 3, one type of ship-

ping case to which my improved method is applicable, is formed from three blanks. 55 The main blank is creased and slotted to form the bottom 7, two side walls 8, two cover flaps 9 and flanges 10 and 15 along each longitudinal edge, adapted to lie flat upon end panels 11 formed separately. 60 Each of the end panels 11 has a cover flap 12 and a bottom flange 13, adapted to be secured to the bottom 7 of the box.

In the manufacture of the shipping cases, after the main and end blanks have been 65 formed by scoring, slotting and trimming, the main blank is laid flat and the end blanks are placed upon the bottom panel 7, so that the flanges 13 overlap said panel. Now, by driving wire stitches 14, the end blanks are 70 secured to the main blank and the flat assembly of blanks is shipped to the packer, who erects the boxes by my improved method as they are needed.

My improved method can be best carried 75 out by the use of a table 16 having as the rear portion thereof two side wings 17, separated by a central opening 18. These wings 17 are arranged to support a stack 19 of the blanks in substantially upright position. A 80 suitable support 20 for the blanks is provided at the back of the table and a stop 21 is secured to the top of the table to prevent the blanks from sliding toward the front edge 24. The opening 18 in the table is wide 85 enough to receive the projecting end walls 11, as shown in Figs. 1 and 4. Within the forward portion of the opening 18 is an inclined member or cam 22, adapted to engage the lower walls 11 and to fold them as hereinafter described. Near the front edge of 90 the table is an offset plate 23, upon which the bottom wall 11 is supported to permit the passage of the flanges 10 beneath said wall.

When the shipping case is to be constructed from an assembly of blanks, such as that shown in Fig. 3, a stack of such blanks are supported upon the wings 17 of the table with one end wall 11 of each projecting into the central opening 18 and the blanks resting upon the edges of the flanges 10 and 10^a. The normally outer surfaces of the blanks are placed so as to face an operator stationed at the front edge 24 of the table 16. The successive folding operations 100 upon each blank A are illustrated in Figs. 105

1, 6 and 4. As shown in Fig. 1, the first operation consists in folding the flanges 10 and 10^a at right angles to the main blank along its upper and lower edges. This can be readily accomplished by the operator grasping the upper edge near the junction of the cover flaps 9 with side panels 8 and by applying pressure downward upon the wings 17 of the table. Thus, the flaps 10 and 10^a at the top and bottom edges of a blank are simultaneously folded along their crease lines. The blank A is now drawn towards the operator so that the end panel 11 strikes the inclined member 22 and is folded to its position perpendicular to the bottom 7, thus bringing the blank to the position shown in Fig. 6. Simultaneously with the folding of the lower side 11 upon the table, the upper side 11 may be folded manually 20 to extend parallel to the bottom panel 11. Now the free edges of the upper flanges 10 are raised so as to pass above the panel 11 and the side panels 8 are folded toward each other and away from the operator, simultaneously, to the position shown in Fig. 4. During this last mentioned folding operation, the end wall 11 upon the table is offset upward by the plate 23 so as to permit the free passage of the lower flanges 10 beneath the margins of said wall 11. By merely grasping the box at its upper corners extending away from the operator, the side walls 8 are pressed inward upon the end panels 11 and the anvil of a stitching machine may be inserted in the open top of the box which is retained in its position remote from the operator. Rows of stitches 25 and 24 at one end of the box may now be driven. Finally, the box is inverted and the anvil is inserted in the other end where the corresponding stitches are driven. Now the box is complete and is ready for filling.

My improved method insures proper positioning of the several flanges, preparatory to the permanent securing operation and has the added advantage of saving much time in erecting the boxes. Further, by attaching the several blanks of each case together before shipping to the packer, I minimize the cost of shipping by making it possible to transport the boxes in the most compact form and greatly facilitate their erection after they are received by the packer.

It will be evident that means other than the table 16 may be employed to facilitate the folding operation and it is even possible to carry out this invention entirely manually if a plurality of operators are available.

Having described my invention what I

claim as new and desire to protect by Letters Patent is:

1. The method of constructing shipping cases having side and end walls formed from a plurality of blanks, at least one of said blanks having flanges along its opposite edges adapted to overlap the other blanks at the ends of the case, which method consists in first overlapping the several blanks along an edge of each and securing them together while flat, subsequently folding said flanges inward simultaneously at the opposite edges of said blank, then folding the end walls to final position, then folding the side walls inward to bring said flanges into overlapping relation with the end walls and finally securing said flanges upon the margins of said end walls.

2. The method of constructing shipping cases having side and end walls formed from a plurality of blanks, one of said blanks having portions constituting the bottom, two side walls and flanges along its opposite edges adapted to overlap the other blanks at the ends of the case, which method consists in first overlapping the several blanks along an edge of each and securing the blanks together while flat, subsequently folding said flanges inward at the opposite edges of said blanks, then folding an end wall inward to position perpendicular to the bottom, then folding the side walls inward to bring said flanges into overlapping relation with the end walls and finally securing said flanges upon the margins of said end walls.

3. The method of constructing shipping cases having side and end walls formed from a plurality of blanks, one of said blanks having flanges along its opposite edges adapted to overlap the other blanks at the ends of the case, which method consists in first overlapping the several blanks along an edge of each and securing the blanks together while flat, subsequently setting up said blanks upon an edge of each and folding said flanges away from the operator simultaneously at the opposite edges of said blanks, then folding the end panels away from the operator to final position, then folding the side panel walls away from the operator to bring said flanges into overlapping relation with the end walls and finally securing said flanges upon the margins of said end panels.

In testimony whereof, I have hereunto signed my name to this specification.

PAUL F. BOEYE.
